UNITED STATES PATENT OFFICE.

JULES ERNEST ROULEZ, OF PARIS, FRANCE.

ELECTRICAL APPARATUS FOR REPRODUCING SOUNDS.

SPECIFICATION forming part of Letters Patent No. 450,426, dated April 14, 1891.

Application filed October 9, 1890. Serial No. 367,553. (No model.) Patented in France February 4, 1890, No. 203,907.

To all whom it may concern:

Be it known that I, JULES ERNEST ROULEZ, a citizen of the Republic of France, residing in Paris, France, have invented certain Im-
5 provements in Electrical Apparatus for Repro-
ducing Sounds, (for which I have obtained a
French patent, dated February 4, 1890, No.
203,907,) of which the following is a specifica-
tion.

10 The improved electrical sound-carrying or
sound-conveying apparatus forming the ob-
ject of the present invention is employed for
reproducing speech and other sounds at a dis-
tance. The said apparatus is constructed
15 with a membrane or diaphragm of a material
which is a semi or imperfect conductor of
electricity and one or more blocks of the same
or like material directly attached to the said
membrane, but electrically insulated there-
20 from, and containing in cavities provided for
the purpose, being open on the side turned
toward the membrane, a body or material
through which the electric current is caused
to pass, and which is composed of powder or,
25 preferably, filaments of semi-conducting ma-
terial less than one millimeter or one twenty-
fifth of an inch in section.

The following are characteristic features of
this apparatus: first, intimate and complete
30 union of the vibrating membrane or dia-
phragm with the blocks, so as to form one
piece attached to the support solely by the
edges of the membrane or diaphragm; sec-
ond, the formation of a hollow or vacant space
35 in front of the said vibrating membrane with-
out exposing the latter to accidental shocks,
but so as to concentrate the sound-waves and
involve and bring into play the entire sur-
face of the said membrane, in order to pro-
40 duce a more considerable effect; third, the
employment as intermediary part or electrical
connection between the membrane and the
insulated blocks of filaments of semi-conduct-
ing material of less than one millimeter in
45 section.

In order that my said invention may be
fully understood, I shall now proceed more
particularly to describe the same, and for that
purpose shall refer to the several figures on
50 the annexed sheets of drawings, the same let-
ters of reference indicating corresponding
parts in all the figures.

Figure 1 of the accompanying drawings
represents in elevation the back of the mem-
brane composed of semi-conducting material 55
and provided with one insulated block. Fig.
2 represents the apparatus in vertical sec-
tion, the section being taken on the line 1 2,
Fig. 1; and Fig. 3 represents a horizontal sec-
tion on the line 3 4, Fig. 1. 60

The apparatus is provided with a circular
membrane or diaphragm M, of semi-conduct-
ing material (retort - carbon, agglomerated
carbon, graphite, or the like) and of suitable
dimensions, according to the degree of sensi- 65
tiveness to be obtained in the instrument.
To this membrane a block B, of the same semi-
conducting material, is attached by means
of screws v, suitably insulated. In the block
B are formed cavities or cells b in the side 70
toward the membrane, which are filled with
short or broken filaments of semi-conducting
material of less than one millimeter in sec-
tion. These filaments may be replaced by the
same material in the form of dust or powder, 75
but with less advantage. The block B is ins-
ulated from the membrane M by a sheet or
plate c, of non-conducting material, perforated
with as many holes as there are cells in the
block, so that the filamentary substance or 80
material b is in direct contact with the mem-
brane. The membrane, being thus provided
with one or more blocks B, is placed on a
board or support A, about four or five milli-
meters, or, say, one-fourth inch, thick, perfo- 85
rated with a circular aperture slightly smaller
than the diameter of the membrane, so that
the latter may be attached by its edges to the
support.

In order to secure the membrane in posi- 90
tion, a metal washer or ring a is employed,
which is placed over the edges of the mem-
brane and secured by screws d, screwed into
the support A. This support is covered by
another board or plate P, which is relatively 95
thin, and is perforated with a central hole p
of any suitable dimensions. This plate forms
between itself and the membrane a vacant
space or chamber of about the same width as
the thickness of the support A, so that the 100
entire surface of the membrane is bare and
the membrane is free to vibrate under the
influence of the sound-waves that may im-
pinge against it. Finally, the apparatus is

- placed in communication with any suitable source of electricity by means of conductors x and y . The current enters by the membrane and leaves by the block, or vice versa.
- 5 When the sound-waves strike the membrane, the resulting vibrations, owing to the way in which the parts are connected together, are transmitted to all the other parts simultaneously and without shock. The arrangement 10 of the apparatus consequently has the effect of obviating the hissing or frizzing and other disadvantages resulting from unstable contacts, which prejudice the clearness or sharpness of the sounds.
- 15 The intensity of the apparatus is regulated by reducing the diameter of the hole p or by providing it with a mouth-piece. In the former case the intensity is diminished. In the latter case it is augmented.
- 20 This apparatus may be constructed of any suitable form and dimensions, and any suitable material may be employed in the construction of its constituent parts, or they may be combined with the supplementary parts of
- 25 microphones, commutators, electro-magnets, and the like.

Having now particularly described and ascertained the nature of my said invention and in what manner the same is to be performed, I declare that what I claim is—

- 3c 1. A microphonic or other similar electric apparatus with a membrane or diaphragm M , of semi-conducting material, having one terminal conductor connected to it, in combina-

tion with one or more insulated blocks B , to which the other conductor is connected, these blocks being also of semi-conducting material and secured to and supported solely by the said membrane, substantially as hereinbefore described.

2. A microphonic or other similar electric apparatus having a vibrating membrane M , to which one terminal conductor is connected, in combination with insulated blocks B , secured to and carried wholly by the said membrane and having cells b , containing filaments of semi-conducting material, the other terminal being connected to said blocks, substantially as hereinbefore described.

3. An electrical apparatus for reproducing or conveying sound with a vibrating membrane or diaphragm M , having rigidly attached to it near its edges one or more insulating-blocks B , supported solely by said diaphragm, the intermediate or connecting body between the said membrane or diaphragm being composed of broken filaments not exceeding about one millimeter in section, and one terminal conductor being connected to the diaphragm, while the other is connected to the blocks, substantially as described.

In testimony whereof I have signed my name to this specification in the presence of two subscribing witnesses.

JULES ERNEST ROULEZ.
